PORTABLE RADIO

Richard Cubertson, Manlius, N.Y., assignor to
General Electric Company

Filed June 25, 1970, Ser. No. 23,676

Term of patent 14 years

Int. Cl. D14—03

U.S. Cl. D56—4

FIG.1

FIG.2

FIG.3

FIG.4

FIG.5

FIG.6

FIG. 1 is a front elevation view of a portable radio in accordance with my design;

FIG. 2 is a front elevation view with the top cover closed;

FIG. 3 is a top plan view;

FIG. 4 is a bottom plan view;

FIG. 5 is a side elevation view; and

FIG. 6 is a rear elevation view.

The front surface is completely covered with a uniform arrangement of holes as fragmentarily shown in FIGS. 1 and 2. Portions of the drawing in FIGS. 1, 3 and 6 are diagonally lined to indicate a transparent surface.

I claim:

The ornamental design for a portable radio, as shown and described.
